Primary Examiner — Zenia Bennett(74) Attorney, Agent, or Firm — Polson Intellectual Property Law, PC; Margaret PolsonCLAIM

The ornamental design for braided bracelet closures, as shown and described.

DESCRIPTION

FIG. 1 is a top plan view of my new design for a braided bracelet closure.

FIG. 2 is a bottom plan view of FIG. 1.

FIG. 3 is a right side elevation view of FIG. 1.

FIG. 4 is a left side elevation view of FIG. 1.

FIG. 5 is a front elevation view of FIG. 1.

FIG. 6 is a back elevation view of FIG. 1; and,

FIG. 7 is a top perspective view of the braided bracelet closure in the closed configuration.

The dashed and dotted lines are an unclaimed border and the broken lines showing the continued length of the braid and the closure cord are for illustrative purpose only and form no part of the claimed design.

1 Claim, 2 Drawing Sheets(56)
